(57) **CLAIM**

(21) Appl. No.: **29/309,937**

The ornamental design of a heat collector assembly for sprinkler head, as shown and described.

(22) Filed: **Nov. 14, 2008**

DESCRIPTION

(30) **Foreign Application Priority Data**

May 16, 2008 (JP) 2008-012241

FIG. 1 is a front view of the heat collector assembly for sprinkler head;

(51) **LOC (9) Cl.** 23-01

FIG. 2 is a back view thereof;

(52) **U.S. Cl.** D23/213

FIG. 3 is a right side view thereof;

(58) **Field of Classification Search** D23/213,

FIG. 4 is a plan view thereof;

D23/214; 169/37, 38, 39

FIG. 5 is a sectional view taken along 5—5 in FIG. 1;

See application file for complete search history.

FIG. 6 is a front view of the heat collector assembly for

(56) **References Cited**

sprinkler head of FIG. 1 mounted on a sprinkler head; and,

U.S. PATENT DOCUMENTS

FIG. 7 is a plan view of the heat collector assembly for

4,134,458 A * 1/1979 Kimura 169/37

D399,553 S * 10/1998 Kumagai D23/213

6,098,718 A * 8/2000 Sato 169/37
